UNITED STATES PATENT OFFICE.

LEE DE FOREST, OF NEW YORK, N. Y., ASSIGNOR TO DE FOREST PHONOFILM CORPORATION, OF NEW YORK, N. Y., A CORPORATION OF DELAWARE.

MEANS FOR SHIELDING SOUND DETECTOR AND AMPLIFIER APPARATUS.

Application filed April 28, 1923. Serial No. 625,337.

This invention relates to means for shielding sound detectors and high tension amplifying apparatus from disturbances due to electro-magnetic or electrostatic disturbances.

5 ances.

The object of the invention is to provide means of this character which is simple in structure, efficient in operation and economical in manufacture.

10 Further objects of the invention will appear more fully hereinafter.

The invention consists substantially in the construction, combination, location and relative arrangements of parts, all as will be 15 more fully hereinafter set forth as shown in the accompanying drawing, and will be more fully outlined in the appended claims.

Referring to the drawing the single figure represents the means embodying my invention for shielding a sound detector and 20 amplifying apparatus from extraneous electric disturbances.

Referring to the drawing, reference characters 1 and 2 designate microphones or the 25 like, for example of the carbon granular electrostatic electro-magnetic type, thermo or ionic type. In other words, the microphones are diagrammatically illustrated, and may be of any standard or desired type, and I 30 do not desire to be limited or restricted in this respect.

It is frequently of advantage to use two or more sets of microphones, either screwed together or scattered about the room where 35 the sound waves are being picked up. I have shown in the illustration two such microphones grouped together, but I do not desire to be limited or restricted in this respect. Each microphone or group of microphones, in accordance with my invention, 40 is enclosed in an open mesh metallic casing 3, and the wires leading to the microphones are encased in metallic conduits, sheaths or the like, 4, which is in electrical contact 45 with the enclosing mesh case 3. The mesh case 3 thus forms a complete shield against electrostatic and electro-magnetic induction, and at the same time allows the sound waves to pass freely therethrough to the microphones.

Reference numeral 5 designates an amplifier apparatus which may be of any suitable type, for example, an audion amplifier system, and in accordance with my invention 55 I propose to provide a metal casing 6 there-

for. The sheaths 4 for the connecting wire is in contact with the metal case 6, and the cage 3, and the metal case 6 when used is connected to ground 7.

As will be readily apparent upon inspection, the leads from the microphones pass through metal sheath 4 and are connected to the binding face of the amplifying apparatus 5 in the usual well known manner. The outlay wires from the amplifying apparatus are illustrated at 8.

It will be understood that the cage 3 and the case 6 are both grounded. Inasmuch as the sheath 4 is in metallic contact with both cage 3 and case 6, it is likewise grounded. 70 Where the cage 3 and the case 6 are employed together a common ground for both of them is thus made possible. It will be understood, however, that when the cage 3 is employed alone, a separate ground connection is supplied therefor.

Many changes and modifications will readily occur to those skilled in the art without departing from the spirit and scope of my invention, as defined in the claims; but having now set forth the objects and nature of my invention and having shown and described a structure embodying the principles thereof, what I claim is new and useful and of my own invention, and desire to secure 85 by Letters Patent is:—

1. The combination with a microphone device, of means immediately associated with said device for shielding said device against electrical disturbances while allowing free 90 access thereto by sound waves.

2. The combination with a microphone device of a metallic shield immediately associated with said device which offers negligible opposition to sound-waves, and a ground 95 connection for said shield.

3. The combination with a microphone device, of a wire cage immediately enclosing said device, and a ground connection for said cage.

4. The combination with a microphone device, of amplifying apparatus electrically connected thereto, of means for shielding said device, and said apparatus and their connection against electrical disturbances.

5. The combination with a microphone device, of amplifying apparatus electrically connected thereto, of a metallic shield for said device, apparatus and connection for shielding the same against electrical dis- 110

turbances and a ground connection therefor.

6. The combination with a microphone device, of amplifying apparatus electrically connected thereto, of a metallic shield for said device, apparatus and connection for shielding the same against electrical dis-

turbances, said shields being in metallic contact with each other, and a common ground connection for said shields.

In testimony whereof I have hereunto set my hand on this 25th day of April A. D., 1923.

LEE DE FOREST.
